Watson E. Coleman

UNITED STATES PATENT OFFICE.

HENRY ENNIS, OF LAYLAND, WEST VIRGINIA.

ATTACHMENT FOR ELECTRIC FLASH-LAMPS.

1,185,893.

Specification of Letters Patent.

Patented June 6, 1916.

Application filed November 24, 1915. Serial No. 63,212.

To all whom it may concern:

Be it known that I, HENRY ENNIS, citizen of the United States, residing at Layland, in the county of Fayette and State of West Virginia, have invented certain new and useful Improvements in Attachments for Electric Flash-Lamps, of which the following is a specification, reference being had to the accompanying drawings.

10 This invention relates to an improved attachment for electric flash lamps, the primary purpose being to provide simple and efficient means for opening the clogged or obstructed gas tube of miners' lamps and 15 the like.

It is a more particular object of the invention to provide in combination with a pocket flash lamp, a rod or needle mounted for longitudinal shifting movement upon 20 one side of the lamp case and adapted to be projected beyond the end of the case adjacent to the lamp bulb so that said needle can be readily engaged in the illuminated end of the tube of the carbid lamp.

25 It is another important object of the invention to provide improved means for mounting the sliding needle and protecting the same against distortion or injury when not in use.

30 It is a further general object of the invention to provide a device of the above character which shall be simple, convenient and serviceable in actual use and capable of manufacture at relatively small cost.

With the above and other objects in view, my invention consists in the novel features of construction, combination and arrangement of parts to be hereinafter more fully described, claimed and illustrated in the accompanying drawing, in which,

Figure 1 is an edge view of an electric flash lamp having my improved attachment thereon illustrating the manner of using the same; Fig. 2 is a side elevation; Fig. 3 is a view of the opposite side of the lamp, the needle case being shown partly in section; Fig. 4 is a section taken on the line 4—4 of Fig. 1; Fig. 5 is a section taken on the line 5—5 of Fig. 2; and Fig. 6 is a detail perspective view of the needle holder.

Referring in detail to the drawing, 5 designates a pocket electric flash lamp of any ordinary or well known type, the lamp case being provided in one end with a lamp bulb, indicated at 6.

Upon one side of the lamp case, a longitudinally disposed guide for the needle

holder to be hereinafter referred to, is secured. This guide is constructed from a single sheet of metal, indicated at 7, and this metal sheet has its central portion longitudinally slotted or cut away as at 8, and opening upon one of the end edges of the metal sheet. Adjacent to the opposite longitudinal edges of this slot 8, the side portions of the metal sheet are bent inwardly toward each other, as shown at 9, such inwardly extending portions being spaced from the contiguous portions of the metal sheet at opposite sides of the slot 8, whereby the guide flanges 10 are formed. The opposite portions of the metal sheet are forced toward each other, thereby bending or bowing the medial portion of the sheet extending from the inner end of the slot 8 to the opposite end of the metal sheet into substantially semi-circular form, whereby a shield or housing 11 is produced. The wall of this housing is provided with an opening 12 for a purpose to be later referred to.

In the guide above described, a slide member is mounted, said member being formed from a metal plate having an elongated intermediate cylindrical portion 13 and laterally extending flanges 14 which are engaged beneath the flanges 10 on the guide. It will be understood that the guide is soldered or otherwise securely attached to the side of the lamp case. In the cylindrical portion 13 of the slide member, a rod 15 is rotatably mounted, one end of said rod being provided with a sleeve or enlargement 16 bored to receive a needle or rod 17. A set screw 18 is threaded in the wall of said sleeve for binding engagement with the needle to securely hold the same in connection with the rod 15. The other end of said rod is provided with a suitable head 19 which is preferably knurled so that the rod can be conveniently rotated.

Upon the side wall of the lamp case adjacent to the housing 11, a guide 20 of similar form to the slide member above described, is securely fixed, and through the same the needle 17 extends.

On the opposite side of the lamp case, a suitable case or container 21 is secured to receive a number of needles 17 and a suitable screw driver, whereby the screw 18 may be readily loosened when it is necessary to remove a needle and replace the same by another.

22 designates the switch button for the electric lamp, and 23 a sliding latch member

mounted on the case adjacent to the button and adapted to engage said button and hold the same in a depressed position during the use of the lamp.

5 In the practical use of the invention, the slide member is moved in its guide until the set screw 18 is disposed immediately beneath the opening 12 in the housing 11. By means of a suitable screw driver, said screw 10 may be tightened upon the end of a rod or needle 17 which has been fitted through the guide 20 and into the bore of the sleeve 16. The operator holding the carbid lamp between the knees, now depresses the button 15 22 and moves the latch 23 over the same so that the light rays from the bulb 6 will be thrown upon the end of the gas tube indicated at T, of the carbid lamp L. It will be understood that my invention may be used 20 in connection with any of the various types of miners' carbid lamps. After the needle 17 has been inserted into the end of the tube, the knurled head 19 is engaged by the finger and turned whereby the needle is rotated 25 and any obstruction or clogging of the gas in the tube is broken up or dislodged so that the carbid will feed freely into the lamp chamber. After using the device, the slide member is moved in the opposite direction 30 in the guide 7 and the point of the needle drawn into the tubular guide 20. The housing or shield 11 covers the inner portion of the needle and entirely eliminates any liability of the same being accidentally broken 35 or distorted. It will thus be seen that I have devised a very simple, serviceable and highly convenient attachment for the ordinary pocket electric flash lamp whereby the miners, without assistance, may readily and 40 quickly fill their carbid lamps or open the gas feed tube thereof. As the guide and protecting shield for the needle are constructed from a single sheet of metal, it will be appreciated that the device may be manufactured and attached to the ordinary electric flash lamp at small cost. It is, however, 45 to be understood that I reserve the privilege of mounting the sliding needle for movement upon the lamp case in various other 50 ways than that specifically shown and described herein. The device is also susceptible of many other modifications in the several detail features thereof, and I, therefore, also reserve the right of adopting all 55 such legitimate changes therein as may fairly fall within the spirit and scope of the invention as claimed.

Having thus fully described my invention, what I desire to claim and secure by 60 Letters Patent is:—

1. The combination with an electric flash lamp, of a valve cleaning needle slidably mounted upon the exterior of the lamp case

and adapted to be projected beyond a lamp bulb in the end of the case, and means for 65 manually rotating said needle when the same is projected to its operative position.

2. The combination with an electric flash lamp, of a slide mounted upon the exterior of one of the side walls of the lamp case, a 70 valve cleaning needle rotatably mounted in said slide, and means for manually rotating said needle when the slide is moved to project said needle to its operative position.

3. The combination with an electric flash 75 lamp, of a slide mounted upon the exterior of one of the side walls of the lamp case, a valve cleaning needle rotatably mounted in said slide, means for manually rotating said needle when the slide is moved to project 80 said needle to its operative position, and a housing fixed to the wall of the case adapted to receive the point of the cleaning needle when the same is moved to an inoperative position.

4. The combination with an electric flash lamp, of a slide member mounted exteriorly upon one side of the lamp case for longitudinal movement, a rotatable holder mounted in the slide member, a valve cleaning 90 needle fixed in said holder and adapted to be projected beyond the lamp bulb in the end of the slide when the slide is moved in one direction, said holder and cleaning needle being adapted to be manually rotated 95 in the operative position of said needle.

5. The combination with an electric flash lamp, of a guide secured to one side of the lamp case having a housing formed on one end, a slide member longitudinally slidable 100 in said guide, a holder rotatably mounted in the slide member, and means for detachably connecting a needle to said holder whereby said needle may be projected beyond the lamp bulb when the slide is moved in one 105 direction.

6. The combination with an electric flash lamp, of a guide secured on one side of the lamp case and having a housing on one end, a slide member movable in said guide, a rotatable holder mounted in the slide member, means for detachably connecting a needle to said holder, and a separate guide for said needle fixed upon the lamp case, said needle being adapted to be projected beyond 115 the lamp bulb in the movement of the slide member in one direction and inclosed and protected by said latter guide and the housing when the slide is shifted in the opposite direction.

In testimony whereof I hereunto affix my signature in the presence of two witnesses.

HENRY ENNIS.
